UNITED STATES PATENT OFFICE.

CHARLES B. KILBY AND MAURICE REINITZ, OF BROOKLYN, AND ALBERT B. CLISSON, OF SYRACUSE, NEW YORK, ASSIGNORS TO THE PROSPERITY COMPANY, INC., OF SYRACUSE, NEW YORK, A CORPORATION OF NEW YORK.

SHIRT-PRESSING MACHINE.

Application filed January 8, 1926. Serial No. 80,081.

This invention relates to pressing machines, and particularly coat shirts or garments that are fastened or buttoned down the front, and are open the full length thereof.

- 5 The invention consists in the particularly simple and efficient arrangement of the ironing surfaces whereby a damp garment can be stretched, and held stretched on the buck, and all the wrinkles removed, or the garment so 10 stretched that all the wrinkles are removed during the pressing operation, and none pressed into folds.

The invention consists in the novel features and in the combinations and constructions 15 hereinafter set forth and claimed.

In describing this invention reference is had to the accompanying drawings.

Figure 1 is a plan view of the buck of the 20 pressing machine embodying our invention.

Figure 2 is a side elevation of such machine.

Figure 3 is a plan view similar to Figure 1 showing a shirt on the lower buck, and a fragmentary portion of the press head in its position assumed during the pressing operation.

25 Figure 4 is a plan view of the buck with a neck band clamp omitted for pressing the backs of shirts or blouses, and the like.

Figure 5 is an elevation of the buck.

30 Figure 6 is a detail view of the tail holder shown in Figures 1 and 3.

Figure 7 is a view similar to Figure 3 of a 35 lower buck for ironing the back of shirts with the shirt thereon, a fragment of the press head being also shown.

As is well known to those skilled in the art, the pressing of articles such as coat shirts, especially when damp as they come from the extractor is difficult as when in such damp or 40 wet condition, the articles must be smoothed out by stretching them on the buck and held in such stretched position until the pressing operation begins. Furthermore in the pressing machines heretofore used it has not been

45 possible to iron the entire front and back including the tails. Therefore, one of the objects of this invention is the provision of a buck for such pressing machines, that is platen presses, by which articles such as coat 50 shirts can be stretched when in damp condition so that when pressed there are no wrinkles or creases.

The pressing machine comprises, generally, cooperating pressing elements one of which is

movable toward and from the other, and one 55 being a buck and the other a press head, one of these elements being rectangular in general form and having cut-outs at the shoulder corners thereof so that the shoulder portions of the shirt are not pressed when the front or 60 the back is pressed and do not interfere with the stretching of the shirt on the buck. The pressing of the sleeves and shoulders is done on another machine or in another operation. Either one or the other or both of the pressing 65 elements may be formed with the shoulder cut outs but preferably the lower buck is so formed as the shoulder cut outs on the lower buck also facilitate the stretching of the 70 shirt, or a damp shirt, on the buck. However 75 the upper buck is also formed with cut outs, but when the lower buck is so formed with the shoulder cut outs, those in the upper buck are not of importance. Also the press head is 80 preferably of greater area than the buck, that 75 is the margins of the press head extend beyond the margins of the buck. In machines for ironing shirt fronts the buck is formed with a neck band holder or clamp and in machines for ironing the backs the buck is not provided 85 with such neck band holder or clamp.

In machines of this type usually the buck is stationary and the head movable toward and from the buck. The machine may be of any suitable form, size, and construction, and 85 in the machine here illustrated 1 designates the buck, and 2 the head or platen movable toward and from the buck. The buck is mounted upon a goose neck 3, which in turn is mounted upon the frame 4 of the machine. 90 The head 2 is carried by a yoke or lever 5 pivoted at 6 between its ends to an upright, forming an extension of the rear leg 8 of the machine. The head is carried at the front end of the yoke or lever 5 and the counter- 95 balancing weight 9 is carried by a rear arm of said lever.

The yoke or lever 5 is actuated by any suitable mechanism, here shown as toggle mechanism designated by the numeral 10, which 100 is actuated from a cam shaft 11, the latter being in turn actuated by an electric motor 12. The operation of the toggle mechanism or the shaft 11 by the motor 12 is controlled by a handle 13. The pressing machine per 105 se forms no part of this invention only in so far as the pressing operation of a pressing machine is considered different from that

of an ironing board, and the ironing operation of a platen in pressing machines differs from sliding of an iron on an ironing board. In pressing machines the shape of a buck or head is of vital importance, and of no importance in the ironing boards where the wrinkles are smoothed out by the sliding action of the iron. The goose neck 3 is here shown as mounted at the extreme end of the buck in order that the entire front or back of the shirt, including the tail may be ironed at one operation. In other words the location of the goose neck permits the buck to be so supported that the entire shirt front or shirt back can be laid upon the buck.

The buck is rectangular in general form and is provided with cutouts 14 at the shoulders, and also with a neck band clamp or holder 15 at one end thereof. Also the end 20 of the buck at which the neck band holder 15 is located is tapered and the shoulder cutouts 14 are located at the base or inner end of the tapered portion, that is, the ends toward the middle part of the buck. The buck is also provided with the usual padding 16. The neck band holder or clamp may be of any suitable form, size and construction to hold the neck band while the shirt is being pulled or stretched on the buck, that is this 30 neck band holder is merely an anchor to pull against. The head 2 is formed with a cutout or recess 17 for receiving the neck band holder when the head 2 is in pressing position, and also with shoulder cutouts 18. The head 2 is also of greater area than the buck 1, that is its margins 19 extend beyond the edges of the buck.

The tail holder is located between the ends 40 of the buck and near the ends remote from the neck band holder, or remote from the shoulder cutouts, that is it is located below the pressing surface of the buck 1 or is embedded in the padding 16.

When a shirt or blouse is in normal position, that is a position assumed when being worn, the front edges lap, but when being pressed in order to press both front edges, they cannot be lapped during the pressing operation, and therefore in order to press or iron 50 the coat shirt, it must be stretched on a buck in an abnormal position. When pressing the front of the shirt, the operator, after fastening the neck band on the neck band holder without buttoning it, but with its ends spaced apart on the neck band holder, pulls on the front and tail of the shirt, first pulling with her hands in line with the edges, thus stretching out any wrinkles in the edges of the shirt. She then pulls on the tail portions of the 55 shirt against the end edges of the buck adjacent to the collar band holder, and owing to the shoulder cutouts such pulling can be done without straining the shoulders. After being so stretched the tail is pressed by the 60 hands in engagement with the tail holder

and owing to the location of the tail stretcher the entire shirt front or blouse can be arranged on the buck in position to be pressed.

The machine is then actuated and the press head comes down on the buck. Owing 70 to the cutouts 14 in the buck, the shoulders are not pressed. In so far as this function is concerned, the cutouts in the buck facilitate the proper stretching of the shirt front or back on the buck. Owing to the margins 19 of the 75 head extending beyond those of the buck, the shirt is completely ironed to the extreme edges of the buck. The back of the shirt is ironed in the same way on a buck shown in Figure 7, in which the buck is not provided 80 with the collar band holder.

The backs of the shirt are ironed in the same way as the fronts, but no tail holder is necessary as there are no edges similar to the front edges of the shirt to be held stretched 85 and the ironing operation is merely an ordinary flattened one.

In Figure 3 a shirt is shown as stretched on the buck, and its position assumed when the front is being ironed, and in Figure 7 the back 90 is shown on the buck in position to be pressed. Owing to the shape of the buck 1 a damp shirt can be quickly arranged thereon and the wrinkles removed preliminarily to the pressing operation, and owing to the location of 95 the tail holder practically the entire front or back of a shirt including the tails can be pressed. The tail holder 21 is spring pressed and comprises a strip 22 extending transversely of the buck with its working face substantially flush with that of the buck or the padding thereon so that the tail of the shirt can be readily caught onto the tail holder when the shirt is lying on the buck, the tail holder being embedded in the padding of the buck or located in a channel formed in the padding. The strip 22 is formed with upwardly extending prongs of comparatively fine wire and is usually a piece of carding. The strip 22 is held in a suitable holder or 105 back 23 which is supported by springs 24.

The springs 24 encircle rods or bolts 25 extending through lugs 26 on the buck and through the end portions of the backing for the strip 22, which end portions extend beyond the front and rear edges of the buck. The upper ends of the bolts extend above the plane of the ironing face of the buck in order to be engaged by the overhanging margins of the head as the head is being brought down 110 onto the buck, but before the head comes completely down onto the buck, thus the bolts 25 and hence the back 23 and strip 22 are depressed so that the prongs on the strip 22 are carried out of the fabric of the shirt.

What we claim is:—

A pressing machine for pressing coats, shirts and the like, comprising pressing elements, one having relative movement toward and from the other, one of said elements being 130

a buck and the other a press head; and the head and the buck being of oblong form, said buck having a tapered end portion provided with means for holding a neck band and having at the inner end of the tapered portion cutouts at the shoulder corners of the buck.

5 In testimony whereof, we have hereunto

signed our names in the borough of Brooklyn, city, county and State of New York, this 21st day of November, 1925.
